(57) CLAIM

I claim the ornamental design for a calf nursery, as shown and described.

DESCRIPTION

FIG. 1 is a front and right side perspective view of a calf nursery showing my new design;

FIG. 2 is another perspective view thereof showing a hatch in a fully open position;

FIG. 3 is a rear and left side perspective view thereof;

FIG. 4 is a top plan view thereof;

FIG. 5 is a back elevation view thereof;

FIG. 6 is a front elevation view thereof;

FIG. 7 is a right side elevation view thereof; and,

FIG. 8 is a left side elevation view thereof.
